UNITED STATES PATENT OFFICE.

ALEXANDER KONOFF, OF NEW YORK, N. Y., ASSIGNOR TO VOICES INCORPORATED, OF WILMINGTON, DELAWARE, A CORPORATION OF DELAWARE.

POST STRUCTURE FOR VOICE DEVICES.

Application filed December 30, 1922. Serial No. 609,929.

This invention relates to a sounding device for dolls and other toys, and particularly to a standard or post structure employed in such devices. The post of the present invention being in the nature of an improvement upon what is shown and described in my pending application Serial No. 570,209 filed June 22nd, 1922, sounding device for dolls and toys.

10 The object of the present invention is to provide a post upon which the bellows head may slide, adapted for accomplishing the same purposes as set forth in the said co-pending application, namely of guiding and supporting the bellows head, and of controlling the passage of air through the sounding device, and said post being also constructed to provide a continuous unbroken wear surface along which the bellows head may slide.

15 20 A further object is to provide a post which is cheaper to manufacture and lighter in weight than the post heretofore used.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a preferred form of embodiment of the invention:

Figure 1 is a vertical sectional view, partly diagrammatic illustrating the post of this invention, and its associated parts.

40 Figure 2 is a perspective view of the post detached and,

Figure 3 is a perspective view similar to Figure 2, illustrating a modified arrangement with openings in the post.

45 Referring to the drawings, for describing in detail the structure therein illustrated, the reference character L indicates the cylindrical housing closed at its upper and lower ends by cover parts 1 and 2, and containing 50 the bellows 3, being a movable head 4. The head 4 is a central opening 5, by means of which it is slidably mounted upon the post G.

The head 4, cases the sound producing element H, in substantially the same relation as described in co-pending application, that is the inner end of said element extends into the bellows while the outer end opens into a sound box 6, formed as a part of the head, the passage of air through the sound producing element, and through the sound box being controlled by features of the post as the head slides along the post.

55 60 The post of the present invention is made from a length of suitable tubing, preferably metal tubing.

65 At an appropriate point in its length it is fitted with a disk 7, which closes communication between opposite end portions of the interior of the tube.

70 75 Above the disk 7, the walls of the tube are formed with openings 8, cut therethrough, and below the disk the walls of the tube are formed with similar openings 9. These openings extend longitudinally of the tube and may be of any appropriate lengths as may be found desirable or necessary for producing certain sounds as will be readily understood with this art. In the instance illustrated, in which the device is 80 intended to produce the sound Ma-Ma, the openings 8, are relatively shorter than the openings 9.

75 80 The opposite ends of the tube are open, but when the tube is in aperture position within the casing L, said ends are closed by being received in retaining pockets 10 of the covers 1 and 2, said retaining pockets not only operating to close the ends of the tube but also to retain tube in a rigid upright position within the casing.

85 90 The portions as 11 of the tube, intermediate openings 8, and the portions as 12, intermediate openings 9, serve to provide continuous and unbroken wear surfaces longitudinally of the tube along which the head 4 may slide without any likelihood of being retarded by engagement of the projecting portions of the post as is the case in said co-pending application. The necessity for an 100 extended sleeve, as in said co-pending application, is thereby dispensed with.

95 105 It is intended that the opening 5, which continues through the wall 14 of the head, shall be sufficiently large so as to provide a passage, as 13 through which air may pass

from the sound box in a quantity sufficient to permit movement of the head freely past unapertured portions of the post.

The operation of the device may now be readily understood: When the device is upset, then the head 4, moves by gravity along the post to bring the outer wall 14 of the sound box beyond the ends of the aperture 8. Then, as the device has returned to its upright position, the force of gravity immediately moves the head downwardly, meanwhile pressing out air from the bellows through the sounding device and the sound box, and through the passage 13. Initially the sound produced by the reed escapes in restricted volume through this passage 13 to simulate the sound of the letter "M." While the wall 14 is moving past the apertures 8, then the sound from the chamber 6 flows freely through apertures 8 into and out of the interior of the post, and thus produces a simulation of the sound of the letter "A" which continues until the wall 14 passes beyond the aperture 8, and encounters the unapertured portion 15 of the post in the region of the disk 7 where the volume of sound emitted is again restricted. As the wall 14 continues to move along the post it uncovers the apertures 9 and the free flow of sound into and out of the post is again established and the simulation of the sound of the letter "A" is repeated.

It will be understood that by placing additional separate disks, as 7, spaced apart along the length of the tube, and providing apertures through the tube communicating with the space between said disks, then the sounding of the sound producing device may be repeated as often as desired.

40 The casing L may be provided with suitable openings therethrough for permitting passage of sound outwardly from within the casing.

45 In the instance illustrated the cover 1 of the casing is shown to be provided with aperture 16 for this purpose.

In the modification, Figure 3, the post is identical with the post already described, except that its apertures 8 and 9 are arranged to extend longitudinally at an angle relative to the longitudinal axis of the tube.

50 A post constructed in this manner will present a continuous wear surface to all portions of the circumference of the guiding opening 5 of the bellows head so that said guide opening will receive substantially uniform wear in all its parts.

As many changes could be made in this construction without departing from the scope of the invention as defined in the following claims, it is intended that all matters contained in the above description or shown in the accompanying drawings shall be interpreted as illustrative and not in a limiting sense.

Having thus described my invention, what I claim as new and desire to secure by Letters Patent is:—

1. In a sound producing device, a casing having an air chamber, a sounding reed, a weighty member movable in said casing by gravity to expel air from said chamber through the reed, a hollow post mounted in said casing and guiding the movement of the weighty member, said post having longitudinally spaced series of openings in the wall thereof, means fixed within the post between said two series of openings and preventing the flow of air therebetween through said post, and means on said weighty member co-operating with said two series of openings and the wall of the post to control the emission of sound produced by the reed through said openings and the interior of the post.

2. In a sound producing device, a casing having an air chamber therein, a sound producing reed, a weighty member movable by gravity in the casing to expel air from said chamber through the reed, and means for controlling the emission of sound produced by said reed including a hollow guide post for the weighty member fixed with relation to the casing walls and having longitudinally spaced openings in the wall thereof, a disk fixed within said post and preventing communication between said openings interiorly of the post, and a sound receiving chamber on said weighty member having a wall cooperating with the wall of said post and the spaced openings therein to control the emission of sound through said openings.

3. A sound producing device comprising a casing having an air chamber therein, a sound producing reed, a weighty member movable by gravity in said casing to expel air from the chamber through said reed, a hollow guide post for said weighty member extending axially through the casing and the air chamber and provided with longitudinally spaced openings in the wall thereof, means preventing communication between said spaced openings interiorly of the post, and said weighty member having a sound receiving chamber provided with a wall coacting with the wall of said post and with the spaced openings therein to control the emission of sound from said chamber in the gravity movement of said head in one direction.

4. A sound producing device comprising a casing having an air chamber therein, a sound producing reed, a weighty member movable by gravity in said casing to expel air from the chamber through said reed, a hollow guide post for said weighty member extending axially through the casing and the air chamber and provided with longitudinally spaced openings in the wall thereof, said openings being elongated and extending circumferentially of the post at an ob-

lique angle relative to the axis thereof, means preventing communication between said spaced openings interiorly of the post, and said weighty member having a sound re-
ceiving chamber provided with a wall co-
acting with the wall of said post and with
the spaced openings therein to control the
emission of sound from said chamber in the
gravity movement of said head in one di-
rection. ¹⁰

In testimony whereof I affix my signa-
ture.

ALEXANDER KONOFF.
